CONTROL MECHANISM FOR OIL-BURNING
SPACE HEATERS

Earl D. Hillebrand and John R. Fulmer, Kankakee, Ill., assignors to Florence Stove Company, Gardner, Mass., a corporation of Massachusetts

Application June 10, 1947, Serial No. 753,684

3 Claims. (Cl. 161—7)

1

The invention relates to control mechanism for oil-burning space heaters and more particularly to mechanism for providing timed control of the fire level of the heater.

One object of the invention is to provide control mechanism of the above general character which may be set to change the burner from a low fire level to a high fire level after the lapse of a predetermined time.

Another object is to provide timing means adapted to operate with a flow control valve of the type commonly used in oil burning space heaters without interfering with the normal functioning of the valve and which is settable to restrict the heater to low fire operation for a predetermined period and then automatically adjust the valve for operating the burner at a preset high fire level.

It is also an object of the invention to provide burner control means which is simple and inexpensive in construction, which is foolproof in operation and which permits accurately timed control of the operation of an oil burning space heater.

Other objects and advantages of the invention will become apparent from the following detailed description of the preferred embodiment illustrated in the accompanying drawing, in which:

Figure 1 is a perspective view of control mechanism embodying the features of the invention and showing the manner in which the mechanism is installed in an oil burning space heater.

Fig. 2 is a partly sectioned side view of the control mechanism showing the parts set for high fire operation.

Fig. 3 is a partly sectioned side view of the control mechanism showing the parts set for low fire operation.

While the invention is susceptible of various modifications and alternative constructions, we have shown in the drawings and will herein describe in detail the preferred embodiment, but it is to be understood that we do not thereby intend to limit the invention to the specific form disclosed, but intend to cover all modifications and alternative methods and constructions falling within the spirit and scope of the invention as expressed in the appended claims.

Referring to the drawing, the improved control mechanism comprises generally a float valve 5 adapted to regulate the flow of liquid fuel, such as oil, to the burner of a space heater, which may be of any preferred type. Fuel oil is delivered to the float valve from a tank or reservoir 6 by way of a pipe 7 and flows from the valve to the burner

through a pipe 8. The tank 6 is preferably mounted at a higher level than the valve to provide for gravity flow of the fuel oil.

The float valve 5 may be of any suitable character, as for example, a valve of the general type disclosed in U. S. Patent No. 2,120,364, granted June 14, 1938, to Roy W. Johnson. Such valves are provided with a casing 10 enclosing a metering valve 11 together with float control means 10 for maintaining a constant head of oil within the casing to insure a uniform flow of oil to the burner.

In the particular valve mechanism illustrated, the metering valve 11 comprises a plunger 12 slidable axially in a tubular body 13 to vary the effective area of a port 14 through which the oil passes on its way to the burner. The plunger is yieldably urged in a direction to open the port 14 by a spring 15 interposed between a partitioning member 16 within the casing 10 and an enlarged head 17 formed on or rigidly secured to the upper end of the plunger.

Cooperating with the plunger 12 is a lever 20 pivotally supported at one end within the casing 10 by a shaft 21 and having a downwardly offset arm 22 overlying the plunger and engaging a pin 23 projecting from the upper end thereof. The arm 22 may be extended beyond the valve for cooperation with other control instrumentalities enclosed in the casing 10 with which the present invention is not concerned.

For adjusting the metering valve 11 to regulate the flow of oil to the burner, a rod 25 is threaded through the top of the casing 10 with its inner end positioned for engagement with the free end of the lever 20. Accordingly, by screwing the rod 25 into or out of the casing, the valve member 12 may be moved up or down to progressively increase or decrease the effective area of the port 14.

The above described adjustments of the metering valve 11 are necessarily effected manually. Thus the adjusting rod is screwed in to almost close the valve port 14 when it is desired to operate the burner at low fire level. When more heat is required, the rod is screwed out to open the valve port 14 and thereby increase the rate of fuel flow to the burner, the latter operating at high fire level when the valve port is substantially fully opened.

In accordance with the invention, timing means is associated with the metering valve 5 in a novel manner, whereby the change from low fire to high fire operation may be effected automatically at a selected and preset time. For this purpose a suitable timing device 30 is mounted

on the valve casing 10 and valve actuating means is interposed between the valve member 12 and the timing device to enable the latter to maintain the valve member in substantially closed or low fire position for a selectively variable time interval and to thereafter release the valve member for movement to the open or high fire position. Under those conditions, the adjusting rod 25 serves as an adjustable stop for determining one limit position of the valve member, that is, the high fire position. To define the low fire position of the metering valve the arm 22 is provided with a stop screw 31 adapted to engage a fixed abutment 32 in the valve casing and thus limit the movement of the lever 20 toward the valve closing position.

The timer 30 may be of any suitable type, as, for example, a simple, inexpensive spring driven twelve-hour timer of the type in general use. The timer as shown comprises a shaft 33 adapted to be rotated manually to selected set positions and then returned from such set positions to a normal rest position at a predetermined rate by spring driven mechanism. The timer shaft is journaled in and projects from the under side of a housing 34 which serves to enclose the driving mechanism. A setting member 35 in the form of a rod projects from the upper side of the housing.

In the exemplary control mechanism, the means through which the timer operates to actuate the metering valve 11 comprises a cam 36 fast on the lower end of the timer shaft 33, a lever 37 adapted to be rocked by the cam and a sliding member or pin 38 for transmitting the movement of the lever to the valve actuating lever 20. As herein shown, the lever 37 is formed with an offset end section 39 adapted to seat against a flat surface 40 formed on the underside of a boss 41, depending from the timer housing 34. The end section of the lever is apertured to loosely receive a screw 42 threaded into the boss 41 and a spring 43 interposed between the head of the screw and the lever yieldably holds it flat against the surface 40, as shown in Fig. 2.

At its free end the lever 37 is provided with an adjustable stop screw 44 cooperating with the upper wall of the casing 10 to limit the movements of the lever toward the operated position in which it is shown in Fig. 3. The pin 38 is retained in an aperture in the top of the valve casing 10 with its lower end resting on the arm 22 of the valve actuating lever 20 and the downward movement of the lever 37 is thus transmitted through the pin and lever 20 to the metering valve member 12.

For rocking the lever 37 to the operated position and for retaining it in such position for a predetermined timed interval, the cam 36 is formed to provide a cam track cooperating with a follower pin 45 rigid with the lever. The cam track as shown comprises an annular flat surface 46 perpendicular to the axis of the timer shaft 33 and an upwardly offset or recessed surface 47 connected together by an inclined surface 48. The arrangement is such that when the timer is at the zero or normal rest position, the cam surface 47 is presented for engagement by the follower 45 and the spring 43 is effective to hold the lever 37 in the retracted position shown in Fig. 2. The metering valve is held in its open or high fire position, as defined by the stop 25, through the action of the spring 15.

As the rod 35 is rotated to set the timer, the cam 36 is turned (from right to left as viewed

in Fig. 2), causing the follower 45 to ride up the cam surface 48 and onto the flat surface 46, whereby the lever 37 is rocked to the operated position shown in Fig. 3. This movement is transmitted through the member 38 and lever 20 to the metering valve member 12, which is accordingly shifted to the low fire position defined by the adjustable stop 31. In practice, the stop screw 31 is set so that the valve is able to pass only sufficient oil to keep the burner in operation.

The metering valve is maintained in the low fire position with the follower 45 riding on the cam surface 46 until the cam is turned back almost to its normal rest position by the action of the timer driving mechanism. As the cam approaches its rest position, the follower 45 rides down the cam surface 48 and thus permits the metering valve to open and increase the rate of oil flow to the burner very gradually, so as to allow the burner to heat up sufficiently to handle a maximum supply of fuel. Delivery of excess fuel to the burner with its resultant smoke and carbon formation is thus eliminated.

The improved control means is adapted to be mounted on the casing 50 of an oil burning heater in the manner shown in Fig. 1. As the float valve 5 is intended to be located substantially at the same level as the burner, that is, near the base of the heater, the stop rod 25 and the timer setting rod 35 are extending upwardly for convenient access near the top of the heater. As herein shown, the rods are arranged to project through a suitable guide 51 on the back of the casing 50 and are provided with knobs 52 and 53 for manual manipulation. Graduated scales on the guide cooperate with the knobs to visually indicate the setting of the metering valve 11 and the setting of the timer 30.

It will be apparent from the foregoing that the invention provides control mechanism of a novel and advantageous character. Through the novel arrangement of a simple timing device with a conventional float valve, the heater may be set for low fire operation for a predetermined interval, as, for example, through the night, and is automatically adjusted for high fire operation at the proper time. The advantages of this mode of operation will be readily appreciated as it permits the heater to be turned up for maximum heat production at a desired time without manual intervention. The mechanism is simple and inexpensive in construction and foolproof in operation.

We claim as our invention:

1. A control mechanism for oil burners comprising, in combination, a metering valve having a member movable between high fire and low fire positions for regulating the flow of oil to a burner, spring means yieldably urging said valve member toward the high fire position, means for adjusting the position of said valve member within predetermined limits including a shiftable control element, lever means interposed between said control element and said valve member, stop means coacting with said lever to define one of said limits, a timer adapted to be set for varying time intervals, said timer having a cam shiftable through a range corresponding to the setting of the timer and returned to a rest position at the end of the interval for which the timer is set, and other lever means interposed between said first-mentioned lever means and said cam operable to move said valve member to the low fire position when said cam is shifted from said rest position, said valve member be-

ing released to the control of said spring means and said control element upon return of said cam to rest position.

2. A control mechanism for oil burners comprising, in combination, a metering valve having a member movable between high fire and low fire positions for regulating the flow of oil to a burner, spring means yieldably urging said valve member toward the high fire position, means for adjusting the position of said valve member including a shiftable control element, lever means interposed between said control element and the valve member, an adjustable stop member limiting movement of said lever toward low fire position, a timer adapted to be set for varying time intervals and acting through said lever means in response to such setting to move said valve mem-

ber to the low fire position irrespective of the position of said control element, said timer acting after the interval for which it was set to release said valve member to the control of said spring means and said control element.
